UNITED STATES PATENT OFFICE

107,020

DESIGN FOR A COMBINED HOSE TOWER AND CABINET FOR AUTOMOBILE SERV- ICE STATIONS OR SIMILAR ARTICLES

Willis A. Kropp, Oak Park, Ill., assignor to Stew-
art-Warner Corporation, Chicago, Ill., a cor-
poration of Virginia

Application July 8, 1937, Serial No. 70,301

Term of patent 3½ years

To all whom it may concern:

Be it known that I, Willis A. Kropp, a citizen of the United States, residing at Oak Park, in the county of Cook and State of Illinois, have invented a new, original, and ornamental Design for a Combined Hose Tower and Cabinet for Automobile Service Stations or Similar Articles, of which the following is a specification, reference being had to the accompanying drawings, forming a part thereof.

Figure 1 is a front elevation of a combined hose

tower and cabinet for automobile service stations or similar articles showing my new design;

Figure 2 is a top plan view of the hose tower and cabinet shown in Figure 1; and

Figure 3 is an end elevation of the hose tower and cabinet shown in Figure 1.

I claim:

The ornamental design for a combined hose tower and cabinet for automobile service stations or similar articles, as shown.

WILLIS A. KROPP.
